(57) **CLAIM**

The ornamental design for a multifunction silicone cup, as shown and described.

DESCRIPTION

FIG. 1 is a front, top perspective view of a multifunction silicone cup design showing the first embodiment of my new design.

FIG. 2 is a front view of a multifunction silicone cup.

FIG. 3 is a rear view of a multifunction silicone cup.

FIG. 4 is a left view of a multifunction silicone cup.

FIG. 5 is a right view of a multifunction silicone cup.

FIG. 6 is a top view of a multifunction silicone cup; and,

FIG. 7 is a bottom view of a multifunction silicone cup. Any shading and cross-hatching are not features of the design but are utilized to illustrate the surface contours of the multifunction silicone cup design in the drawings.
